UNITED STATES PATENT OFFICE.

GEORGE HENRY MIDDLEMISS, OF BIRMINGHAM, ALABAMA.

AUTOMATIC RECLOSED MECHANISM.

Application filed June 20, 1924. Serial No. 721,358.

This invention relates to electric current distribution and has special reference to controlling devices for power circuits and particularly to an automatic reclosing mechanism.

In the operation of electric power plants it frequently happens that conditions arise on a circuit which temporarily cause such increase of current as to endanger the transmitting devices connected to the circuit. To prevent injury under such conditions it is usual to provide, at the power house or substation, an overload circuit breaker to afford the proper protection to the line and transmitting devices. I have heretofore devised apparatus for reclosing such circuit breakers, under certain conditions, without the intervention of manual means and such devices and others used in connection with the present invention have been shown and described in my copending applications, 581,749 for automatic switch reclosing devices, 646,883 for switch controlling devices, and 673,865 for power distributing system. Each of the first two of these applications discloses a single circuit breaker or switch controlled by a novel mechanism which involves considerable apparatus and it has been found that the employment of a separate apparatus for each of the switches on a switch panel or board involves considerable complication and expense.

One important object of the present invention is to provide an improved arrangement wherein a single control apparatus may be used to control a series of switches thereby reducing complication and expense.

In the reclosing apparatus forming the subject matter of my prior applications for such devices, the reclosing operation was arranged to take place at fixed time intervals under all conditions. That is to say, the apparatus, being set to reclose in one minute after the circuit is broken, will close the circuit at that time and if the trouble causing the opening of the circuit breaker persists the circuit will again be broken and again reclosed at an interval of one minute. It frequently happens that the trouble is only momentary, lasting perhaps a fraction of a second or just long enough to cause opening of the circuit breaker. To wait one minute for the reclosing then becomes unnecessary and wastes time.

A second important object of the present invention is to provide an improved form of

apparatus for reclosing the circuit the first time much more quickly than the reclosing is effected the second time. For instance, the first reclosing after the circuit breaker trips may be arranged to take place at an interval of from two seconds to one minute in accordance with the setting of the apparatus. If the trouble has disappeared at the time of this reclosing there will be no further tripping of the circuit breaker, but if the trouble persists after the first reclosing the circuit breaker will trip a second time and then the reclosing will be effected at a time interval of one minute thus allowing the contacts of the switch to cool, the gases in the switch to dissipate and the other parts of the switch to assume normal temperatures, so that, if the trouble still continues after this second reclosing, the switch will be in better condition to accomplish the third breaking of the circuit the third time.

Figure 1 is an elevation showing an apparatus constructed in accordance with this invention.

Figure 2 is a front view of a gang of such switches connected to a single reclosing device.

Figure 3 is a detail elevation showing the reclosing device and one of the switch controls in closed position.

Figure 4 is a detail elevation similar to Figure 3 but with the reclosing device in a different position and a certain telescopic link of the switch controlling device expanded.

Figure 5 is an enlarged detail view showing the switch controlling device in opened position.

Figure 6 is a detail view showing the action of the trip mechanism.

Figure 7 is a section on the line 7-7 of Figure 5.

Figure 8 is a view similar to Figure 1 showing a modified form of the device.

Figure 9 is an enlarged detail view of the trip mechanism shown in Figure 8, the view being partly in section.

Figure 10 is a view similar to Figure 1 but showing a second modification of the arrangement.

Figure 11 is a view showing a further modification in plan, the view being diagrammatic in character.

Figure 12 is a detail elevation of part of the mechanism also diagrammatic.

Figure 13 is a diagrammatic view showing

an improved arrangement of reclosing device.

Figure 14 is an enlarged detail showing a side elevation of a certain circuit closer used in connection with the arrangement shown in Figure 13.

Figure 15 is a plan view thereof.

Consider first of all the apparatus for closing and opening one of the switches.

10 In Figure 1 there is disclosed a panel 10 which is supported by suitable frame 11 whereon is mounted a switch 12 from which leads the usual wiring connections 13 and 14. This switch has an operating lever 15 and to the end of this lever and to the frame are pivotally connected the ends of a toggle joint 16. To the center pivot of this toggle is pivoted an arm 17 which passes through the panel and has at its outer or front end 15 a slot 18 provided with an up turned extremity 19 at its front end. On the panel 10 is mounted an overload trip coil 20. The overload trip coil housing carries an arm 21 so positioned that when an overload occurs 20 through trouble on the line this arm will rise and strike the under side of the bar 17 so that the bar is lifted. Pivoted to the trip coil housing 20 is a bellcrank lever having a vertical arm 22 and a forwardly extending arm 23. On the vertical arm is a pin 24 which engages in the slot 19. Above the switch there is provided a bracket 25 and to this bracket is pivoted a latch member 26 which normally engages a pin 27 on the vertical arm 22. The end of this latch member 30 is provided with an inclined surface 28. Pivoted intermediate its ends to the arm 22 is a trip lever 29, the lower end of which lies in the path of a lug 30 carried by the bar 17 while the upper end is provided with a pin 31 which engages the inclined surface 26 in certain conditions of the operation.

At 32 is shown the casing for a reclosing apparatus which may be similar to that 45 shown in my copending application 581,749 or which may be of the type hereinafter shown and described, the latter being preferred as will be understood by what follows. In any event the apparatus is provided with a rotary cam 33 which operates one end of a lever 34 suitably pivoted to operate under the influence of this rotary cam and having one arm which extends out beneath the arm 23, being understood that 50 this description applies to a single switch. However, if two or more switches are used the arm of the lever which is controlled by the cam 33 is fixed to the shaft 35 and similarly the other arm of the lever is fixed to 55 this shaft at a suitable point. The levers 23 and 34 are connected by an extensible telescopic member which has a lower tubular section 36 open at its upper end and pivoted at the lower end to the lever 34. In this 60 tubular section slides telescopically an up-

per tubular section 37. On the section 37 is a collar 38 secured to the section 39 which passes through the collar and secures the same in position. Also this pin acts as the connecting point of a tension spring 40 70 which has extensions down through the tubular section and is connected to a pin 41 at the lower end of the lower section 36.

Now let it be supposed that overload coil 20 operates, through line conditions, to 75 throw up the arm 21. Then this arm will release the bar 17 and permit the same to move forwardly thus letting the lever 15 drop and opening the main switch 12. As this bar 17 moves forwardly the lug 30 contacts with the lower end of the lever 22 and rocks it to knock off the trip 26 from the pin 27. This permits the lever 23 to move outwardly and the bar 17 to drop slightly so that the end 19 again engages the pin 24 85 thus connecting the bar 17 in such manner that when the lever arm 23 is moved upwardly the switch will be again closed. If the device 32 operates prior to the energization of the coil 20 then the sleeve 36 90 will be pulled down thus placing the spring 40 under tension. Under these circumstances the trip coil 20, in operating, will act as previously described and the lever arm 23 will be quickly jerked down. 95

Now considering further the arrangement as shown in Figure 2 it will be seen that, instead of a single switch a gang of switches, four in number, has been shown and that these are arranged to be operated by a single reclosing apparatus. These different switches are all of the type just described and each controls an individual circuit. These switches are indicated respectively at A, B, C and D. Under normal conditions 100 of operation all the switches are closed. If, now an overload occurs on the line controlled by switch A then the breaker of this circuit trips and by wiring connections 105 which will presently be described, the auxiliary switch closes. This starts the reclosing device and under the influence of the cam of that apparatus the rock shaft 35 rotates so that the several telescopic rods are pulled down. Since the lever arm 22 of switch A 110 has been unlatched this arm now swings out but the lever arms of the other switches do not swing out since they remain latched. Instead the extensible rods are extended. As the reclosing apparatus continues to operate the cam turns to such position that the lever 34 is permitted to rise and thus the switch mechanism A closes quickly and smoothly. 115

If, during the time the switch A is open, 120 one of the other circuits be so affected as to open its overload circuit breaker and thus effect release of its lever arm 22, the spring 40 of that switch will collapse the extended 125 expandible link and the lever arm 22 will be 130

quickly swung to forward position so that closing movement of the lever 34 will close that switch at the same time as the switch A is closed. Of course, if trouble persists on any circuit the switch pertaining to that circuit will again open, the remaining switches staying closed. It is obvious that any number of switches may thus be reclosed by a single reclosing apparatus.

10 In other words, if two or more breakers open simultaneously all will remain open for the same length of time but if two or more breakers open in succession within the time set for closing after the first of these opens 15 (say one minute) then all will be closed one minute after the first opens.

The foregoing description applies to a reclosing device wherein a cutout gear train such as is shown in Figure 4 of my prior application 581,749 and including the elements indicated by the reference characters 20 to 29 inclusive is employed. However, under certain conditions such a cut out will interfere with the full operation of the device to 25 always close all the switches. This may be understood if it is considered that the cut out of the automatic reclosing device is so geared that the reclosing mechanism cuts out after three consecutive operations. Under 30 such conditions it may be assumed that switch A opens, followed at intervals of one minute by the consecutive opening of switches B, C and D. Then the reclosing apparatus would lock out after switch C had 35 been reclosed and switch D would not be reclosed. Again, if there should be persistent trouble upon the line connected to switch A, the reclosing apparatus would lock out after three consecutive operations of this switch 40 and the reclosing device would become inoperative as regards the remaining switches.

In order to overcome this objection to the operation of a gang of switches or circuit breakers by such a reclosing device, the cut-out mechanism may be omitted from the reclosing device and certain modifications may be used in the panel supported elements.

One such modification is shown in Figures 8 and 9 wherein the parts are in most respects identical to like parts in Figure 1 except that an electric trip mechanism is used in place of the mechanical latch trip there shown. In this case the lever arm 22 is provided with a pin 42 which is engaged by a latch 43 attached to the core of a solenoid 44 and as seen in the diagram, one terminal of this solenoid is attached by a wire 45 to a main 46 while its other terminal is connected to said main 46 by a wire 47, a notching relay 50 coil 48 being arranged in series on the last mentioned wire. From the neutral main 49 a wire 50 leads to the wire 47 through one pair of the contacts of the notching relay and through one pair of the contacts of the auxiliary switch 20, the remaining pairs of

contacts of said switches being connected to the main 49 and wire 50 by a wire 51.

The notching relay above referred to is a device for controlling the opening and closing of circuits wherein a closed circuit will 70 only be opened after a definite number of energizations of the relay magnet or solenoid. Such a relay is well known in the art and a type thereof is shown in G. E. Review, 1919, vol. 22, page 899.

75

Assuming that the notching relay used is such as to open the circuit controlled thereby after two consecutive energizations and that switch A opens. Then the auxiliary switch will close and current will flow 80 through the tripping solenoid 44 thus releasing the arm 22. This, of course, will not affect the other switches of a bank or set. Also, the closing of the auxiliary switch will start the reclosing device and reclose the 85 switch A as previously set forth. Persistent trouble effects successive openings of the switch A and after two energizations of the relay coil the contacts will open so that the auxiliary switch 20 for switch A will be disconnected from the recloser. The remaining switches B, C and D will be unaffected by this cutting out of switch 20 for A and thus will continue in effective condition for reclosing operations should any one or more 95 of said switches open. Thus any of the circuit breakers will, under persistent trouble, cut itself out without affecting the remaining breakers.

90

Another modification of this arrangement is that shown in Figure 10. In this form, the bell crank lever on the front of the panel is replaced by a straight lever 52 which is connected by a link with one arm of the bell crank 53 pivoted to the bracket 105 54 mounted on the back of a panel. The link 55, connects the remaining arm of this bell crank with one arm of a second bell crank 56 pivoted to a floor stand 57. The remaining arm of this second bell crank is 110 connected by a link 58 with one arm of a third bell crank 59 which is pivoted to a floor stand 60 and has its remaining arm connected by a link 61 with the oil breaker switch 12. The casing for the reclosing 115 apparatus is shown at 62 and on the main shaft 63 of the apparatus is mounted a trip free mechanism 64 such as is shown and described in my copending application No. 673,865 filed November 9, 1923. The arm 65 120 of this device is provided with a slot 68 which engages over a pin 67 fixed on the link 61.

115

A second arm 68' is fixed to the shaft 63 and is actuated by the cam 69.

125

In connection with this figure a typical wiring diagram is shown wherein a notching relay and auxiliary contact switch are employed as described in connection with Figure 8. However, the wiring in the pres-

130

ent modification is somewhat different as will now be seen. The connections to the mains are indicated at 69 and 70 and from the connection 69 extends a wire 71 while a 5 wire 72 leads from 70. A wire 73 leads from wire 72 to one of a pair of normally open contacts 74 in the notching relay 75. From the other of this pair contacts a wire 76 leads to the solenoid or trip coil of the 10 trip release mechanism 64, a wire 77 connecting the remaining terminal of said solenoid with a wire 78 leading to the motor of the reclosing device in the casing 62. Also a wire 80 connects the wires 71 and 72 15 and interposed in series in this connection is a pair of normally closed contacts 81 in the notching relay a pair of normally open contacts 82 in the auxiliary contact switch 84, and the operating coil of the notching 20 relay. In like manner a wire 86 connects the wires 71 and 78 through normally closed contacts in the notching relay and normally open contacts in the auxiliary contact switch.

25 With the arrangement shown in this modification it will be readily understood that the action is the same as that of the modification shown in Figures 8 and 9 except that the cut out of any switch 12 from 30 operation is effected by the notching relay closing the contacts 74 and thus establishing a circuit through the solenoid of the trip mechanism 64. A trip release relay 87 is also provided which includes a fixed contact 35 88 and a movable contact 89 held against the fixed contact by current flowing through the relay coils, these being connected to wiring 90 leading from the coil 20. The contact 88 is connected by a wire 91 with the 40 wire 76 and the contact 89 is connected by a wire 92 with the wire 72. Thus energization of the relay 87 will establish a circuit between the wires 72 and 78 and through the solenoid of the trip mechanism 64 each 45 time the coil 20 is energized.

The action now is as follows:—If the breaker A trips from an abnormal current in the circuit connected to it the trip coils in the circuit connected to it the trip coils 20 on the panel are energized and the 50 breaker mechanism is released at that point. Simultaneously the solenoid of the trip release 64 is energized and the trip release freed from the shaft 63. These two tripping actions effect a complete release of 55 the link and bell crank system and the breaker drops open. As soon as the breaker drops open the auxiliary contact switch closes, thus putting the reclosing device into operation.

60 As soon as the breaker trips, the circuit connected thereto is "killed", and current no longer stays in the trip circuit. Therefore, the trip release relay contacts are open, and as gang shaft 63 rotates, the ratchet 65 wheel inside trip release housing re-engages

with the roller, and as gang shaft moves for closing operation of breaker, the trip release housing and lever arm are carried with it, thus effecting a closing of the breaker.

The notching relay is provided with an 70 additional set of contacts, so that, say, after two consecutive operations, two of the sets of contacts are open, and the other set of contacts is closed. Now assume persistent trouble upon the circuit controlled by 75 breaker 1, then the notching relay will disconnect auxiliary contact switch after two consecutive reclosings, but will likewise close contacts to energize the trip release coil, so that in case any other breaker trips 80 out, the latch release coil of breaker 1 is energized, thus effecting a disconnection of the housing from the gang shaft, and therefore transmitting no motion to breaker 1.

The same principle of operation applies 85 for any other breaker connected to the gang shaft.

In Figures 11 and 12 a still further modification is diagrammatically shown. In these figures the several parts are much like 90 the last arrangement except for certain auxiliary switches and wiring as will now be described. Each main switch (of which only two are here shown) or breaker carries with it a movable member 93 which opens and 95 closes connection between two contacts 94. One of these contacts is connected to a feed wire 95 and the other to a wire 96 leading to the motor of the reclosing device, a wire 97 also leading to this motor. On the panel 100 or face plate are the trip coil solenoids and their plungers as shown at 98. The connections to these coils are not deemed necessary to show in this modification as they have already been described. Each plunger is arranged to close an auxiliary switch 99 connected in series to the coil of a trip free mechanism 64 by a wire 100 and to the wire 97 in multiple by a wire 101. Also each trip free mechanism is connected to the wire 95 110 by a wire 102.

The reclosing device proposed has a special duty cycle as follows:—When breaker trips automatically, same will be reclosed within ten seconds. If trouble persists, and 115 breaker trips the second time, same will be reclosed thereafter at the end of one minute. The time interval for the first reclosing can be varied from one minute to five seconds, in accordance with customer's wishes, but subsequent consecutive reclosings have a one 120 minute interval.

The operation is as follows:—

Suppose breaker B trips automatically; switch rod of breaker B will drop to open 125 position and trip coil of trip release mechanism will move so that ratchet wheel to shaft immediately engages the trigger. The closing of the auxiliary contact switch on breaker B starts the reclosing device and, in ten 130

seconds, the movement of the roller along the vertical face of the cam closes breaker B. Breaker A, not having opened, the switch rod is as shown in closed position, 5 and shaft in ratchet wheel idly rotates in trip release mechanism.

Suppose persistent trouble on circuit connected to breaker B; then first reclosing is performed as described above, but as soon as breaker B is reclosed the first time, face plate trip coil immediately operates and its contacts close to energize the coil of trip release mechanism, lifting trigger to permit opening of breaker. The auxiliary switch, of course, immediately closes when breaker opens and the reclosing device continues in operation so that in one minute the movement of the cam roller along the vertical face of the cam, closes breaker B the second time. At this point, tripping occurs again, but a small further movement of the reclosing device opens the lockout switch and further reclosing is stopped.

Under gang operation, if breakers A and B open simultaneously, both will be reclosed in ten seconds. If breaker B opens and ten seconds thereafter breaker A opens, then breaker B will be closed in ten seconds and breaker A will be closed in one minute. If there is persistent trouble on the circuit controlled by breaker B, and reclosing device locks out, then breaker A is non-reclosing until an operator can be sent to the station to disconnect the control wiring of breaker B and reclose lockout switch for reclosing of breaker A, should same open.

In the above arrangement it is to be noted that the switches perform the same duty as the trip release relay before described.

In Figures 13, 14 and 15 is shown the arrangement whereby the reclosing device acts to make its first reclosing in a much shorter time than the subsequent reclosing. This operation is preferably termed a "recovery cycle" and is accomplished by the addition of a certain circuit closer to the apparatus fully described in my copending application 581,749 and particularly illustrated in Figure 4 of that application. Figure 13 is substantially a duplicate of the just mentioned figure of the copending application with certain additions and wherever necessary to refer to parts of the apparatus common to both the reference characters formerly used will be here used with the addition of a lower case letter "a".

In Figure 13 then, the main shaft is indicated at 19^a and is driven by the motor M^a. Also the leads to the reclosing device are shown at 42^a and 43^a. Mounted upon the shaft 19^a is a commutator 104 which may be insulated from the shaft and is provided with a notch 105 in its periphery. Adjacent this commutator is fixed an insulating block 106 to which are fixed the ends of

spring fingers or brushes 107 having depressed ends 108 resting on the commutator and dropping into the notch 105 as the latter rotates so that the connection between the fingers is broken upon the notch being reached. One of these fingers is connected by a wire 109 with the lead 42 and the other by a wire 110 with 43^a. Thus these brushes are connected in parallel with contacts 3^a and 4^a which are the same as the contacts 75 of the auxiliary switch previously described and are open in the closed position of the main circuit breaker 12. In operation the tripping of the main circuit breaker closes contacts 3^a and 4^a thus connecting the motor in circuit and starting the reclosing device. At the time of starting the fingers 107 are out of connection as their ends rest in the notch 105 and the cam 33 of the reclosing device is in such position that the roller 12^a is almost ready to drop down the straight side of the cam. Thus a very small movement of the cam trips the lever 34 and recloses the switch as previously described.

The extent of this movement, and consequently the time of reclosing, is regulated by the position of the cam on its shaft 14^a and by the position of the notch 105 because as soon as the reclosing is effected the auxiliary switch contacts 3^a and 4^a open and the motor circuit is opened as far as regards any flow of current through these contacts. However, as soon as movement of the shaft 19^a starts the fingers 107 ride on the commutator surface 104 and the motor is kept in circuit through these fingers until the notch 105 again is in position to open contact between the commutator and fingers whereupon current will cease to flow through the motor until circuit is re-established through the contacts 3^a and 4^a. Thus if the normal reclosing is to be effected one minute after the breaker operates and the notch 105 be positioned so that the commutator makes one twentieth of a revolution before the lever drops, the first reclosing will be effected in three seconds and the second in one minute.

Having thus described the invention, what is claimed as new, is:

1. In combination, a main circuit breaker, a reclosing device including a lever mounted for oscillation and electric motor driven means for oscillating the lever, a second lever pivoted adjacent the main breaker, a link connecting the breaker and second lever and arranged for operative engagement with and disengagement from the second lever, a latch controlling the movement of the second lever in one direction, circuit controlled means to disengage the link and second lever, other means to release said latch from the second lever operable in substantial synchronism with the circuit controlled means.

2. In combination, a main circuit breaker, a reclosing device including a lever mounted

- for oscillation and electric motor driven means for oscillating the lever, a second lever pivoted adjacent the main breaker, a link connecting the breaker and second lever and arranged for operative engagement with and disengagement from the second lever, a latch controlling the movement of the second lever in one direction, circuit controlled means to disengage the link and second lever, 10 a circuit controlled trip for said latch, and a resilient connection between said levers.
3. In combination, a series of main circuit breakers, a reclosing device including an oscillatory lever and electric motor means for oscillating the lever, a rock shaft on which said lever is fixed, a series of rock levers fixed to the rock shaft, operative connections between respective breakers and rock levers each including a resiliently extensible link, 15 and circuit controlled latching means for each connection, each latching means being controlled by circuit conditions in the circuit closed and opened by the respective breaker.
- 20 4. In combination, a plurality of main circuit breakers, a reclosing device, and independent operative connections between the breakers and reclosing device each including an extensible and collapsible link comprising sections, one longitudinally slidably with respect to the other, and means yieldably holding said sections in normal relation to each other, and means to cut out the several operative connections arranged to act on a respective connection upon the connection operating to reclose its breaker a predetermined number of times.
- 25 5. In combination, a plurality of main circuit breakers, a reclosing device, and independent operative connections between the breakers and reclosing device each including a link consisting of a pair of telescopically arranged tubes, and a tension spring yieldably holding the tubes in collapsed relation, 30 and means to cut out the several operative connections arranged to act on a respective connection upon the connection operating to reclose its breaker a predetermined number of times.
- 35 6. In combination, a main circuit breaker, a reclosing device, and an operative connection between said breaker and reclosing device including an extensible and collapsible link comprising sections one longitudinally slidably with respect to the other, and means yieldably holding said sections in normal relation to each other, said reclosing device being provided with electrical control means arranged to effect primary reclosing at a predetermined relatively short time interval and a secondary reclosing at a relatively long time interval.
- 40 7. In combination, a main circuit breaker, a reclosing device, and an operative connection between the breaker and reclosing device and including a link consisting of a pair of telescopically arranged tubes, and a tension spring yieldably holding the tubes in collapsed relation, 45 said reclosing device being provided with electrical control means arranged to effect primary reclosing at a predetermined relatively short time interval and a secondary reclosing at a relatively long time interval.
- 50 8. In combination, a main circuit breaker, a reclosing device including a lever mounted for oscillation, means to oscillate the lever and an electric motor to operate said means, a normally latched trip device, an operative connection between the trip device and lever and including a yieldingly extensible link, an operative connection between the breaker and trip device, and circuit controlled means for unlatching the trip device, said reclosing device being provided with electrical control 55 means arranged to effect primary reclosing at a predetermined relatively short time interval and a secondary reclosing at a relatively long time interval.
- 55 9. In combination, a main circuit breaker, a reclosing device including a lever mounted for oscillation and electric motor driven means for oscillating the lever, a second lever pivoted adjacent the main breaker, a link connecting the breaker and second lever and arranged for operative engagement with and disengagement from the second lever, a latch controlling the movement of the second lever in one direction, circuit controlled means to disengage the link and second lever, other means to release said latch from the second lever operable in substantial synchronism with the circuit controlled means, and a resilient connection between said levers, said reclosing device being provided with electrical control means arranged to effect primary reclosing at a predetermined relatively short time interval and a secondary reclosing at a relatively long time interval.
- 60 10. In combination, a main circuit breaker, a reclosing device including a lever mounted for oscillation and electric motor driven means for oscillating the lever, a second lever pivoted adjacent the main breaker, a link connecting the breaker and second lever and arranged for operative engagement with and disengagement from the second lever, a latch controlling the movement of the second lever in one direction, circuit controlled means to disengage the link and second lever, a circuit controlled trip for said latch, and a resilient connection between said levers, said reclosing device being provided with electrical control means arranged to effect primary reclosing at a predetermined relatively short time interval and a secondary reclosing at a relatively long time interval.
- 65 11. In combination, a plurality of main circuit breakers, a reclosing device, and independent operative connections between the breakers and reclosing device

breakers and reclosing device each including an extensible and collapsible link comprising sections one longitudinally slidable with respect to the other, and means yieldably holding said sections in normal relation to each other, said reclosing device being provided with electrical control means arranged to effect primary reclosing of a respective breaker at a predetermined relatively short time interval and a secondary reclosing of said breaker at a relatively long time interval.

12. In combination, a plurality of main circuit breakers, a reclosing device, and independent operative connections between the breakers and reclosing device each including a link consisting of a pair of telescopically arranged tubes, and a tension spring yieldably holding the tubes in collapsed relation, said reclosing device being provided with electrical control means arranged to effect primary reclosing of a respective breaker at a predetermined relatively short time interval and a secondary reclosing of said breaker at a relatively long time interval.

13. In combination, a plurality of main circuit breakers, a reclosing device, and independent operative connections between the breakers and reclosing device each, a normally latched trip device for each breaker, operative connections between the trip devices and levers and each including a yieldably extensible link, an operative connection between each breaker and its trip, and a circuit controlled means for unlatching each trip device actuated by abnormal conditions in the circuit controlled by the respective breaker, said reclosing device being provided with electrical control means arranged to effect primary reclosing of a respective breaker at a predetermined relatively short time interval and a secondary reclosing of said breaker at a relatively long time interval.

14. In combination, a series of main circuit breakers, a reclosing device including an oscillatory lever and electric motor means for oscillating the lever, a rock shaft on which said lever is fixed, a series of rock levers fixed to the rock shaft, and operative connections between respective breakers and rock levers each including a resiliently extensible link, said reclosing device being provided with electrical control means arranged to effect primary reclosing of a respective breaker at a predetermined relatively short time interval and a secondary reclosing of said breaker at a relatively long time interval.

15. In combination, a series of main circuit breakers, a reclosing device including an oscillatory lever and electric motor means for oscillating the lever, a rock shaft on which said lever is fixed, a series of rock levers fixed to the rock shaft, operative con-

nctions between respective breakers and rock levers each including a resiliently extensible link, and circuit controlled latching means for each connection, each latching means being controlled by circuit conditions in the circuit closed and opened by respective breaker, said reclosing device being provided with electrical control means arranged to effect primary reclosing of a respective breaker at a predetermined relatively short time interval and a secondary reclosing of said breaker at a relatively long time interval.

16. In combination, a plurality of main circuit breakers, a reclosing device, and independent operative connections between the breakers and reclosing device each including an extensible and collapsible link comprising sections, one longitudinally slidably with respect to the other, and means yieldably holding said sections in normal relation to each other, and means to cut out the several operative connections arranged to act on a respective connection upon the connection operating to reclose its breaker a predetermined number of times, said reclosing device being provided with electrical control means arranged to effect primary reclosing of a respective breaker at a predetermined relatively short time interval and a secondary reclosing of said breaker at a relatively long time interval.

17. In combination, a plurality of main circuit breakers, a reclosing device, independent connecting means between each main circuit breaker and the reclosing device, together with disconnecting means operative with each main circuit breaker, independently of the others, said reclosing device being provided with electrical control means arranged to effect the primary reclosing of a breaker at a predetermined relatively short time interval and a second reclosing of said breaker at a relatively long time interval.

18. In combination, a plurality of main circuit breakers, a reclosing device, and independent operative connections between each of the main circuit breakers and the reclosing device, together with means to cut out each of the operative connections after its operation to reclose its main circuit breaker a predetermined number of times, said reclosing device being provided with electrical control means arranged to effect the primary reclosing of a breaker at a predetermined relatively short time interval and a second reclosing of said breaker at a relatively long time interval.

19. In combination, a plurality of circuits, a circuit breaker in each circuit adapted to be opened automatically upon the occurrence of a predetermined condition of the respective circuit, mechanism associated with each breaker arranged to close the

same, driving means common to all of said mechanisms with elastic connections between the driving means and said mechanisms for actuating said mechanisms in response to the opening of any one of said circuit breakers, and means adapted to be operated after a circuit breaker has been

opened a predetermined number of times to prevent the reclosing of said breaker by its respective mechanism.
